PAINT ROLLER END CAP

John A. Pharris, Milwaukee, Wis., assignor to EZ Painter Corporation, a corporation of Delaware
Filed Oct. 24, 1965, Ser. No. 504,494
8 Claims. (Cl. 15—230.11)

ABSTRACT OF THE DISCLOSURE

A paint roller end cap including a hollow cylindrical hub rotatably mounted upon a paint roller axle, a hollow cylindrical rim spaced concentrically outwardly of the hub, and having a perpendicular flange extending inwardly toward the hub, a closure member removably mounted upon one end of the rim and radial webs extending between the hub and rim that are circumferentially spaced to define passage means for allowing fluid to flow outwardly from a chamber formed between an end of the hub and the closure member.

This invention pertains in general to paint applying devices, and more particularly to a new and improved paint roller.

In the past, it has been well known to removably mount a paint applying sleeve on the axle of a paint roller device. Such roller devices have usually included end caps (commonly formed of a suitable plastic material) at opposite ends of the axle that are rotatably mounted thereon, and which telescopically receive the paint applying sleeve. Stop means, such as a washer held by a screw, have been conventionally provided at the outer end of the axle to prevent the end cap on this end of the axle from being removed. A closure member is commonly provided over the outer end of the last mentioned end cap to prevent paint and the like from accumulating around the stop means, and to provide a more attractive finished looking product. The paint applying sleeves which are in common use, usually employ a somewhat porous backing member, and paint remover, paint thinner, and paint itself have exhibited a tendency to seep through the paint applying sleeve, and around the outer ends thereof. Such fluids have commonly run along the axle of the paint applying member, and passed between the hub of the outermost sleeve and the axle, to become trapped in a chamber formed between the hub and the closure member. When the paint applying device is subsequently used with a different color paint, or with a new paint applying sleeve, the fluid trapped in the above mentioned chamber commonly runs outwardly therefrom and through the paint applying sleeve to cause a streaking or discoloration of the paint being applied. Accordingly, the general purpose of this invention is to provide a paint applying device of the character described which eliminates streaking and discoloration of the paint being applied.

A more specific object of the invention is to provide the end cap chamber of a paint applying device as described above with passage means so that undesirable fluids will not accumulate therein.

Another object of the invention is to provide an end cap for a paint applying device which will support a paint applying sleeve for rotation with a minimum amount of friction, and which is extremely sturdy, and relatively inexpensive to manufacture and maintain.

These and other objects of the invention will hereinafter become more fully apparent from the following description taken in connection with the annexed drawing, wherein:

FIG. 1 is a perspective view of a paint applying device utilizing a preferred embodiment of the present invention;

2

FIG. 2 is an enlarged sectional view taken generally along line 2—2 of FIG. 1;

FIG. 3 is a sectional view taken generally along line 3—3 of FIG. 2;

5 FIG. 4 is a sectional view similar to FIG. 2, but showing a typical prior art construction; and

FIG. 5 is a sectional view taken generally along line 5—5 of FIG. 4.

While this invention is susceptible of embodiment in many different forms, there is shown in the drawing and will herein be described in detail one specific embodiment, with the understanding that the present disclosure is to be considered as an exemplification of the principles of the invention and is not intended to limit the invention to the embodiment illustrated. The scope of the invention will be pointed out in the appended claims.

The illustrated embodiment of the paint applying device 10 is shown in FIG. 1 to have a longitudinally extending handle 11, with a rod 12 extending outwardly therefrom and having first portion 13 inclined with respect to the axis of the handle, a second portion 14 generally parallel with handle 11, and a third portion 15 disposed at right angles with respect to handle 11 and defining an axle. A first end cap 16 is provided on axle 15 adjacent rod portion 14, and this end cap may be of any conventional design, and will hereinafter be referred to as the inner end cap. The second end cap 17 is provided at the outer end of the axle 15, and forms the subject matter of the present invention. The end cap 17 will hereinafter be referred to as the outer end cap.

As is well known in the art, a paint applying member 20 is formed generally integrally with a suitable hollow cylindrical backing member 19, which is removably retained on the end caps 16 and 17, as by friction or the like. As is well known, the backing member 19 and paint applying member 20 are somewhat porous, so as to enable fluids to seep therethrough, and around their portions of engagement with the end caps 16 and 17.

The typical prior art end cap construction will be described first, so that the advantages of applicant's construction will be more easily understood. The typical prior art end cap construction 17' is shown in FIGS. 4 and 5 to include a hollow cylindrical hub 22, which rotatably mounts the end cap 17' on the axle 15'. Hub 22 includes an enlarged portion 23 which defines a shoulder 24 against which stop means in the form of washer 25 are seated. The washer 25 is retained on axle 15' as by the outwardly struck portions 26 thereof. End cap 17' further includes a hollow cylindrical rim 27 spaced concentrically outwardly from hub 22, and a flange or end wall 28 connects enlarged hub portion 23 and rim 27. An annular recess 29 is provided in flange 28, and a circular closure member 30 is seated therein. As is clear from FIG. 5, when the closure member 30 is in place, a chamber 32 is formed between the shoulder 24 and the closure member 30. Closure member 30 may be provided with axial extensions 31 that engage the wall of chamber 32 to positively retain the closure member in place. It will be readily apparent that fluid which is present within the interior of the paint applying device will have a tendency to work its way along the bore 33 of hub 22 into the chamber 32. The fluid will then be substantially trapped in chamber 32 during periods when the paint roller is not in use, and when the paint roller is subsequently used, the fluid escapes from chamber 32 along the bore 33 of hub 22 into the interior of the paint applying device, where it then seeps through the backing member 19. As will be readily understood, this results in a streaking and discoloration of the paint being presently applied.

Applicant's device includes a cylindrically shaped hub 40 having an axial bore 41 receiving the axle 15 there-

through to rotatably mount the sleeve 19, 20 on the axle 15. End cap 17 includes a hollow cylindrical wall 42 spaced concentrically outwardly of hub 40. As can be best seen in FIG. 3, wall 42 is substantially longer than hub 40, and hub 40 is spaced adjacent the left hand end 43 of the wall 42. The right hand, or outer end, of end cap 17 includes a radially inwardly extending flange 44 having a central opening 45.

A recess is provided in the outer periphery of wall 42 adjacent the right hand thereof, and is defined by an annular surface 47 disposed at substantially right angles to the axle 15, and a convex surface 48 facing surface 47. Convex surface 48 terminates radially inwardly of the outer periphery of wall 42 to define a somewhat pointed end cap portion 49. A generally circular closure member 50 is provided for the right hand end of end cap 17, and closure member 50 includes a somewhat axially and radially inwardly extending hook portion 51 which is shaped generally complementarily to the recess defined by surfaces 47 and 48. The inner diameter of the closure hook portion 51 is less than the outer diameter of the end cap portion 49, so that the closure member 50 may be snapped into place on the end cap 17. For this purpose, it will be understood, that the closure member 50 is preferably formed of a plastic material having a sufficient amount of resilience to enable the same to be snapped onto the end cap 17, and to be readily removable therefrom. The largest radial dimension of the closure member 50, which exists at the portion thereof sitting over end cap portion 49 is preferably less than, or the same as, the diameter of the other periphery of wall 42 so that the paint applying member can be readily positioned on the end cap 17. It will be readily understood that when the closure member 50 is in place on the end cap 17, a chamber 52 is provided at the right hand end of the end cap 17. Passage means, to be hereinafter described, communicate with chamber 52 so as to prevent accumulation of fluids therein.

A plurality of radially extending webs 53 connect hub 40 with flange 44. Webs 53a are provided on diametrically opposed sides of hub 40 from webs 53, and are shaped generally identically therewith. While two webs 53 and two webs 53a have been shown in the illustrated embodiment, it should be understood that more webs may be provided if desired. As can be best seen in FIG. 3, webs 53 are inclined rearwardly from flange 44 to hub 40, and a surface 54 is provided on the forward face of the webs which is generally perpendicular to the axis of axle 15.

A pair of diametrically opposed webs 55 extend generally radially between hub 40 and wall 42, and include a forwardly extending inclined portion 55a which is integral with flange 44. Webs 55 include surfaces 56 which are disposed at substantially right angles to the axis of axle 15, and which are substantially coplanar with web surfaces 54 and the forward or outer end of the hub 40. Generally cylindrically shaped strengthening ribs 57 are formed integrally with each web 55, and extend axially rearwardly from flange 44 between hub 40 and wall 42. It will be understood, of course, that webs 55 provide transverse rigidity for wall 42 in one direction, while allowing it to compress slightly in a diametrically opposed direction so as to enable the paint applying member to be mounted on the end cap 17.

Means are provided for preventing the end cap 17 from moving axially outwardly of axle 15, and includes an internally threaded bore 60 at the outer end of the axle. A screw 61 is threadably received in bore 60, and a washer 62 is provided under the enlarged head of screw 61. Washer 62 abuts against the outer surface of hub 40, and against the surfaces 54 and 56 on webs 53 and 55 respectively, to prevent the end cap 17 from moving axially outwardly of the axle 15. Movement of the end cap 17 axially inwardly along the axle 15 is prevented by the engagement of the closure member 50 with the head of the screw 61.

The above mentioned passage means for chamber 52 are formed by the open areas between the webs 53, 53a and 55. As can be best seen in FIG. 2, generally segment shaped openings 64 are provided between the outer diameter of the washer 62 and the inner diameter of the opening 45 in flange 44. Thus, any fluid which is present in the chamber 52 will readily and quickly run outwardly therefrom, and the problem of fluid accumulation in the end cap chamber is obviated. Accordingly, it is believed obvious that each of the advantages of the invention have been fully achieved.

I claim:

1. In a paint roller having a handle and an axle disposed at generally right angles with respect thereto; a first paint applying sleeve supporting member rotatably mounted at one end of said axle; a second paint applying sleeve supporting member at the other end of said axle and including, a hollow cylindrical outer wall having first and second ends, a hollow cylindrical hub rotatably receiving said axle therein and spaced axially from the first end of said outer wall to define a chamber therebetween, a closure member removably mounted on the first end of said outer wall outwardly of an end of said axle and closing one end of said chamber, passage means in the other end of said chamber for allowing fluid to flow outwardly therefrom; and a paint applying sleeve telescopically received on said first and second supporting members.

2. In a paint roller having a handle and an axle disposed at generally right angles with respect thereto; a first paint applying sleeve supporting member rotatably mounted at one end of said axle; a second paint applying sleeve supporting member at the other end of said axle and including, a hollow cylindrical outer wall having first and second ends, an annular flange extending radially inwardly from the first end of said outer wall, a hollow cylindrical hub rotatably receiving said axle therein and spaced axially from the first end of said outer wall to define a chamber therebetween, a closure member removably mounted on the first end of said outer wall outwardly of an end of said axle and closing one end of said chamber, a plurality of webs extending between said flange and said hub, said webs being spaced from one another to define passage means in the other end of said chamber for allowing fluid to flow outwardly therefrom; and a paint applying sleeve telescopically received on said first and second supporting members.

3. A paint roller as defined in claim 2 wherein a pair of diametrically opposed webs connect said hub and said outer wall.

4. In a paint roller having a handle and an axle disposed at generally right angles with respect thereto; a first paint applying sleeve supporting member rotatably mounted at one end of said axle; a second paint applying sleeve supporting member at the other end of said axle and including, a hollow cylindrical outer wall having first and second ends; an annular flange extending radially inwardly from the first end of said outer wall, a hollow cylindrical hub rotatably receiving said axle therein and spaced axially from the first end of said outer wall to define a chamber therebetween, a closure member removably mounted on the first end of said outer wall outwardly of an end of said axle and closing one end of said chamber, diametrically opposed inclined webs extending between said hub and said flange, diametrically opposed webs extending between said hub and said outer wall, said last named webs each including an inclined portion extending to said flange, each of said webs being spaced from one another to define passage means in the other end of said chamber for allowing fluid to flow outwardly therefrom; and a paint applying sleeve telescopically received on said first and second supporting members.

5. An end cap for rotatably mounting one end of a paint applying sleeve on an axle comprising: a hollow cylindrical hub adapted to be rotatably mounted on said

axle; a hollow cylindrical rim concentric with said hub and having first and second ends, said rim being longer than said hub and said hub being positioned adjacent said second rim end so as to define a chamber between said hub and the first rim end; web means extending between said hub and said rim; a closure member removably mounted on the first rim end outwardly of an end of said axle and closing one end of said chamber; and passage means in the other end of said chamber between said hub and said rim for allowing fluids in said chamber to pass freely outwardly therefrom.

6. An end cap for rotatably mounting one end of a paint applying sleeve on an axle comprising: a hollow cylindrical hub adapted to be rotatably mounted on said axle; a hollow cylindrical rim concentric with said hub and having first and second ends, said rim being longer than said hub and said hub being positioned adjacent said second rim end so as to define a chamber between said hub and the first rim end; a flange extending radially inwardly from said first rim end; a closure member removably mounted on the first rim end outwardly of an end of said axle and closing one end of said chamber; and a plurality of webs extending between said flange and said web, said webs being spaced from one another to define passage means in the other end of said chamber between said hub and said rim for allowing fluids in said chamber to pass freely outwardly therefrom.

7. An end cap for rotatably mounting one end of a paint applying sleeve on an axle comprising: a hollow cylindrical hub adapted to be rotatably mounted on said axle and having first and second ends; a hollow cylindrical rim concentric with said hub and having first and second ends, said rim being longer than said hub and said hub being positioned with the second hub end adjacent said second rim end so as to define a chamber between the first hub end and the first rim end; a flange extending radially inwardly from said first rim end; a closure member removably mounted on the first rim end and outwardly of an end of said axle closing one end of said chamber;

5 diametrically opposed inclined webs extending between said hub and said flange, diametrically opposed webs extending between said hub and said rim, said last named webs each including an inclined portion extending to said flange, each of said webs being spaced from one another to define passage means in the other end of said chamber between said hub and said rim for allowing fluids in said chamber to pass freely outwardly therefrom.

10 8. An end cap for rotatably mounting one end of a paint applying sleeve on an axle comprising: a hollow cylindrical hub adapted to be rotatably mounted on said axle and having first and second ends; a hollow cylindrical rim concentric with said hub and having first and second ends, said rim being longer than said hub and said hub being positioned with the second hub end adjacent said second rim end so as to define a chamber between the first hub end and the first rim end; a flange extending radially inwardly from said first rim end; a closure member on the first rim end closing one end of said chamber; 15 diametrically opposed inclined webs extending between said hub and said flange, diametrically opposed webs extending between said hub and said rim, said last named webs each including an inclined portion extending to said flange, each of said webs being spaced from one another to define passage means in the other end of said chamber between said hub and said rim for allowing fluids in said chamber to pass freely outwardly therefrom, and each of said webs including a surface generally coplanar with the first hub end to define therewith an abutment adapted to 20 be engaged by stop means carried by said axle.
